LEONARD C. TINGLEY, OF PROVIDENCE, RHODE ISLAND, ASSIGNOR TO M. A. N. MANUFACTURING COMPANY, OF PROVIDENCE, RHODE ISLAND, A CORPORATION OF RHODE ISLAND.

LOCKING-CLAMP.

1,021,343.

Specification of Letters Patent. Patented Mar. 26, 1912.

Application filed September 6, 1910, Serial No. 580,854. Renewed January 17, 1912. Serial No. 671,567.

To all whom it may concern:

Be it known that I, LEONARD C. TINGLEY, a citizen of the United States of America, residing at the city of Providence, in the county of Providence and State of Rhode Island, have invented certain new and useful Improvements in Locking-Clamps, of which the following is a specification, reference being had therein to the accompanying drawing.

This invention relates to locking clamps and refers especially to devices for locking flexible material to rods or bars on which such material is hung.

The especial object of the invention is to provide means for securing against theft such articles as robes and garments when the latter are left in an unoccupied vehicle such as an automobile.

Many vehicles, and particularly automobiles, are provided with rods adapted to support robes or other flexible articles, such as wraps and coats. Such a rod is usually attached at both ends to the back of the front seat of an automobile, the straight portion of the rod being supported far enough from said back to permit folded robes and garments to be hung over it. If the vehicle is left standing, such articles are liable to be stolen.

My invention therefore consists in a lock having jaws adapted to grasp the article and clamp it on the supporting rod, the jaws being then separable only after the use of a key to unlock or release them from their clamping position.

With these and other objects in view, the invention consists of certain novel features of construction, as will be more fully described and particularly pointed out in the appended claims.

In the accompanying drawings: Figure 1— is a front elevation of a clamp or lock embodying my invention. Fig. 2— represents a section on line 2—2 of Fig. 1. Fig. 3— is a side elevation of a key shaped to release or unlock the clamp. Fig. 4— is a perspective view of the device in position, locking a robe on a bar. Figs. 5 and 6— are detail face views of the toothed disks and their carrying members. Fig. 7— is a detail, enlarged, of the interlocking teeth of the disks. Figs. 8 and 9— are side elevations of the upper portions of the two jaws,

separated. Fig. 10— represents a section on line 10—10 of Fig. 5.

Similar reference characters indicate the same or similar parts in all of the views.

The two jaws 10, 11, which are pivotally connected by the locking mechanism presently described, are curved and have their outer ends or tips preferably corrugated or formed with teeth as indicated at 12 in Fig. 2 the teeth alternating with each other in the manner of a suture so as to prevent the fabric of the article from being drawn laterally out from between the lips of the jaws.

The jaw 10 is formed with an integral cylindrical portion hereinafter referred to as the barrel 13, said barrel having one end 14 closed as at 15, said closed end having a key hole 15. The barrel is transversely slotted to receive the ring 16 which is integral with jaw 11. The internal diameter of the portion of the barrel 13 next the bottom or closed end 14 is less than that portion the other side of the slot. To distinguish between these portions, the one of lesser diameter will be referred to as the cup, and the one of larger diameter as the ring 24. In other words, the barrel 13 of jaw 10 presents a cup and a ring separated by a slot in which the ring 16 of jaw 11 fits.

Fitted in the cup of barrel 13 is a disk 17 having a plurality of recesses in which are mounted springs 18 bearing against the bottom or closed end 14 of the barrel so as to have a tendency to press the disk away from said bottom. Pins 19 engaging recesses in the margin of the disk and the inner wall of the cup prevent the disk from rotating in the cup while permitting it to move to and from the bottom thereof. The face of the disk is formed with a circular series of fine radial teeth 20, and is recessed or depressed inside said circular series. The disk is formed with a key hole 21 which registers with the key hole 15 in the bottom or closed end of the barrel. At one side of the key hole the inner face of the disk is inclined to form a cam face 22 for a purpose presently described. This disk will be referred to as the cam disk. Another disk 23 is fitted in the ring 24 of jaw 10 and ring 16 of jaw 11 and is secured in the ring 16 by one or more pins or screws 25. Said disk 23 has a thickness to occupy both rings, and since the ring 24 can rotate

on said disk 23, the disk serves as the pintle on which the two jaws can turn relatively to each other in opening and closing. As said disk has a continuous smooth end surface, it will be referred to as the cap disk to distinguish it from the cam disk.

The inner face of the cap disk is recessed as at 26, has a central socket to receive the end of a key 27, and the face of the disk 10 around the recess 26 is formed with a circular series of radial teeth 28.

The teeth 20 and 28 have abrupt sides and inclined sides as indicated on an enlarged scale in Fig. 7, and face in opposite directions so that they will slip past each other in one relative direction of rotation, but interlock in the other direction. As the springs 18 permit the cam disk 17 to yield away from the cap disk 23, the slip of the teeth past each other will be automatic. The direction in which the teeth face is such that this slip occurs when the jaws of the device are being closed, and the teeth will then automatically interlock at whatever point the closing action stops according to the thickness of material that is grasped between the jaws. And since the jaw 10 can not rotate on disk 17 and jaw 11 cannot rotate on disk 23, said jaws will be locked in their closed position. To release the jaws, a suitable key 27 is inserted in the hole provided therefor, and turned so that, as it rides up cam surface 22, it withdraws disk 17 toward the bottom of the cup, against the pressure of springs 18, and so separates the two series of teeth from each other and unlocks the device, the jaws being then pulled apart to release whatever is grasped thereby.

40 When the parts are assembled as shown in Figs. 1 and 2, and the pins or screws 25 inserted to place, they are held so because the ring 16 of jaw 11 is between cup 13 and ring 24 of jaw 10, and the disk 23 holds them in the manner of the pintle of a hinge. Upon inserting a key of the proper shape and turning it, the wing 29 thereof acts on cam 22 to press the disk 17 away from disk 23, thus separating their teeth. The jaws 50 may then be opened as widely as desired and the key removed. Supposing a robe *a*, or a garment, is hung over a rod or bar *b*, which may be the usual robe rail, or even a foot rail, the device is applied as indicated 55 in Fig. 4 and the jaws pressed firmly against the fabric, binding it on the rod. The teeth 20, 28 ride over each other and interlock, owing to the springs 18. After this, the robe can only be removed after having first 60 inserted the key and turned it, and after the jaws have been pulled apart as indicated by the dotted lines in Fig. 1. It will now be understood that the two disks, with their circular series of teeth, one being movable to and from the other, said disk being

connected to a jaw so that the two disks relatively move rotatively in unison with the jaws, constitute a ratchet mechanism which permits the jaws to close and become locked against spreading at any point according to the amount or thickness of material grasped by the jaws; and that from such point the jaws can only be opened by means of a key used to spread the disks apart to disconnect their teeth so that said ratchet mechanism becomes inoperative.

70 It is to be understood that by the word "key" in the specification and claims I mean any instrument or mechanism by which the lock may be operated.

80 Since the device illustrated, or any obvious modifications thereof, may be employed to clamp other articles than robes, and whether or not the articles are hung on a rod or bar, I do not limit myself to any 85 special use of the device.

I claim:

1. A device of the character described comprising jaws pivoted together, and locking mechanism for holding them against 90 spreading from either one of a plurality of positions, said locking mechanism being adapted to be released by the action of a key.

2. A clamp comprising a pair of jaws, a hub pivotally connecting them, and locking mechanism for holding the jaws against spreading from either one of a plurality of positions, said hub constituting a portion of the locking mechanism, the device being 100 provided with means to permit the operation of a key to release the locking mechanism.

3. A clamp comprising jaws pivoted together, ratchet mechanism for permitting 105 the jaws to close while preventing them from spreading, and a key for rendering said ratchet mechanism inoperative.

4. A clamp comprising jaws pivoted together, ratchet mechanism for permitting 110 the jaws to close while preventing them from spreading, and a key for rendering said ratchet mechanism inoperative, said ratchet mechanism comprising a disk having a circular series of teeth and connected to a 115 jaw to oscillate therewith, one of said disks being yieldingly mounted to permit the teeth to be disengaged by said key.

5. A clamp comprising a pair of jaws having cylindrical bearing portions in axial 120 alignment, a pair of disks each having a circular series of teeth, each disk being secured non-rotatively in one of said cylindrical portions, one disk being movable toward and from the other, and means whereby said movable disk may be disengaged from the other by a key.

6. A robe clamp comprising a pair of jaws having cylindrical bearing portions in axial alignment, a pair of disks each hav- 125

ing a circular series of teeth, each disk being secured non-rotatively in one of said cylindrical portions, one disk being movable toward and from the other, springs normally pressing the movable disk toward the other, and a key for pressing the movable disk away from the other.

7. A robe clamp comprising a pair of jaws having cylindrical bearing portions 10 a disk having a circular series of teeth and fixed in one cylindrical portion, a second disk having a circular series of teeth mounted to move longitudinally but not rotatively

in the cylindrical portion of the other jaw and having a cam surface, means for yieldingly pressing the movable disk toward the other, and a key for acting on said cam surface to withdraw the movable disk from the other one. 15

In testimony whereof I affix my signature 20 in presence of two witnesses.

LEONARD C. TINGLEY.
